UNITED STATES PATENT OFFICE.

VITTORIO BOSCATO, OF DIANO MARINA, ITALY.

IGNITION STARTING DEVICE FOR IGNITION MAGNETOS.

Application filed April 24, 1922. Serial No. 556,320.

To all whom it may concern:

Be it known that I, VITTORIO BOSCATO, a subject of the King of Italy, residing at Diano Marina, Italy, have invented certain new and useful Improvements in Ignition Starting Devices for Ignition Magnetos, of which the following is a specification.

The present invention relates to an ignition starting device for the ignition magnetos of internal combustion engines and more precisely it relates to a tripping gear device fitted on the magneto spindle and serving, even when the engine is running at very low speed, to trip, at a determined moment, a spring forming part of the device and thus to suddenly accelerate the speed of the magneto to obtain an effective spark.

The annexed drawing illustrates one execution form of the invention by way of example.

Fig. 1 is an axial section through the device.

Fig. 2 is a section on the line A—B of Fig. 1.

Fig. 3 is a view of the inside of the device cover.

Fig. 4 shows the box end of the device.

Fig. 5 is an axial section through the said box end.

Figs. 6 and 7 are front views of the stop elements and weights working by centrifugal force.

Fig. 8 is an edge elevation of one of the stop elements.

Fig. 9 is a perspective view of the stop elements removed.

—a— is the magneto spindle actuated by the engine shaft and connected with the magneto. The spindle —a— is connected to a box lid —c— provided with a hub —h— and fixed to the magneto spindle —a— by means of the latter's screw-thread extension —b— and by the screw-nut —d—. —e— is the box end, adapted for connection with the engine shaft and extending into a sleeve —f— embracing the hub —h— and provided with opposed projections —g—. The connection between the lid —c— an the box end —e— is ensured by a spring, whose one end is secured to the lid —c— at —l— and whose other end is secured in a hole formed in the sleeve —f—. The box lid —c— is provided with two slots —m—, diametrically opposite one another and formed near the lid base. Opposed stop elements n and n¹ are movably mount-

ed in the slots m and are provided with curved shank portions o and o' which extend, in opposite directions, partially about the sleeve f and terminate in inwardly directed lugs q and q'. Curved weights p and p' are secured to the lugged terminals of the shanks o and o' and extend to points spaced from the stop elements n, n¹.

Each weight lies on the side of the sleeve f opposite the stop element with which it is connected and thus limits the outward movement of said element through its slot. The ends r and r' of the weights p and p' constitute stops which engage each other when the two stop elements move inwardly. —s— and —t— are two projections secured to the lips of the cover —c— and of the box end —e— in order to limit the amount of rotation of the said cover —c— when the tripping occurs. —u— is a stationary stop designed to cooperate with the tripping mechanism.

The device works in the following manner:

When the engine is running normally, the two stop elements owing to the centrifugal force set up by their weights take a position in which the ends r and r' lie in abutment, and consequently the stop elements —n—, —n¹— do not project out of the slots —m—. With the stop elements so disposed the lid —c— may freely rotate with the box end —e— which latter carries the lid —c— along with it owing to the pressure exerted by the spring —i—.

When the engine is at rest or is running at low speed, as during the starting period, the stop element n with its weight —p— at the top, falls by gravity to the position shown in Fig. 2. The stop element n projects through the slot m formed in the cylindrical portion of the lid c as shown in Fig. 1, and as a consequence during the rotation of the engine, the rotation of this part n is hindered by the stop u and the lid c cannot revolve along with the box end e. The spring i is therefore loaded in tension until one of the projections g of the sleeve f strikes against the stop q and causes the latter to move so that n is released from the catch or stop u. The spring i now sharply pulls the lid c, and along with it the magneto spindle a, into rotation at a sufficient speed for the spark to jump. In order to prevent the lid c flying beyond the desired convenient limit, the lid c is provided with

a stop *s* and the box end is provided with a stop *t*; when the two stops strike against each other, a further undue advance of *c* relatively to *e* is made impossible.

5 The acceleration of the rotation speed sets up sufficient centrifugal force in the weights *p*, *p*¹ to cause the stop elements *n*, *n*¹ to be drawn inside and thus to permit the free rotation of the lid *c* and of the magneto spindle *a*.

Having now particularly described and ascertained the nature of my said invention and in what manner the same is to be performed, I declare that what I claim is:

15 A box including an end member and a lid member provided with a flange engaging the end member and having opposed slots therein, a hub member carried by the lid member adapted to engage the spindle of

20 a magneto, means rotatably supporting the

end member on said hub, the spring means normally maintaining the lid and end members in predetermined angular relation, a relatively stationary stop, opposed stop elements slideable radially through the slots in 25 the flange of the lid member and rotatable with the latter, oppositely curved shank members carried by the stop elements and embracing diametrically opposed portions of the hub and curved weights secured to 30 said shank members, each curved weight embracing a portion of the hub opposite the stop element connected therewith whereby to limit the outward movement of said stop elements.

Signed this 31st day of March, 1922.
VITTORIO BOSCATO.
